UNITED STATES PATENT OFFICE.

WELLINGTON LAURENCE MANSON GENDRON, OF KITCHENER, ONTARIO, CANADA.

VENTILATED FOOTWEAR.

Application filed February 16, 1924. Serial No. 693,325.

To all whom it may concern:

Be it known that I, WELLINGTON LAURENCE MANSON GENDRON, a subject of the King of Great Britain, and a resident of 5 the city of Kitchener, in the county of Waterloo, in the Province of Ontario, Canada, have invented certain new and useful Improvements in Ventilated Footwear, of which the following is the specification.

10 My invention relates to improvements in ventilated footwear, and the object of the invention is to devise a simple cheap device which cannot get out of order, whereby the interior of a boot or shoe may be ventilated, the drawing in and expelling of the air being automatically operated by the alternate pressure and relief of the foot upon the sole of the boot or shoe, and it consists essentially of the arrangement and 15 construction of parts as hereinafter more particularly explained.

Fig. 1 is a longitudinal sectional view through a shoe showing my device incorporated therein.

20 Fig. 2 is a sectional plan view taken directly above the insole and showing the insole and air chamber broken away and partially in section.

Fig. 3 is a cross sectional view on line 25 3-3, Fig. 2.

In the drawings like characters of reference indicate corresponding parts in each figure.

1 indicates the outsole of a boot or shoe. 30 2 indicates the heel, 3 the upper, 4 the counter and 5 the heel stiffening within which is located the lining 6.

The outsole 1 is preferably formed in two layers 1^x and 1°, the layer 1° being cut 35 away to form a chamber 7 located between the instep and the ball of the foot, and over which the greater portion of the foot pressure is exerted during walking.

8 is a channel extending rearwardly from 40 the chamber 7, such channel extending to the rear end of the heel portion 2.

9 is a channel extending forwardly from 45 the chamber 7, provided at its outer end in the point of the toe with an enlargement 10.

11 is an insole located within a boot or 50 shoe so as to form a covering for the chamber 7, the channels 8 and 9, and enlargement 10. The heel end of the insole is 55 notched out at 12, for a purpose which will hereinafter appear.

13 are a series of perforations formed in the insole over the enlargement 10.

14 is a flexible bag forming an air chamber, such bag being preferably made of 60 rubberized cloth. The bag 14 fits the chamber 7, and is provided at its rear end with an orifice 15 opposite to the inner end of the channel 8. The forward end of the bag 14 is provided with a small orifice 16 65 from which extends a tube 17, terminating in a one-way valve 18 formed by the permanent flattening of the tube 17.

19 are a series of rubber tubes cemented 70 in position within the bag 14, such tubes being resilient and serving to expand the bag after each collapsing movement expelling the air therefrom through the valve 18.

20 is a tube located in the channel 8 and 75 extending rearward through the notch 12 of the insole and up the back of the heel between the stiffening and the counter to communicate at its upper end with the atmosphere. The opposite or inner end of the tube is provided with a one-way valve 80 21, which is also formed by the permanent flattening of the tube 18, the walls of the flattened portion being normally in contact, these flattened portions being forced apart by the passage of the air therethrough 85 and contacting together after the passage of the air, thus preventing any return passage. The valves 18 and 21 are what are known in the trade as "Flutter valves." 90

It will thus be seen that by my construction, as the wearer of the shoe walks he alternately exerts and relieves the pressure upon the foot portion of the sole and thereby alternately forces the bag 14 into a collapsed position against the action of the 95 resilient tubes 19, thereby forcing the air contained in the bag outward through the valve into the channel enlargement 10 and through the perforation 13 into the interior of the shoe.

As the pressure is relieved, the bag 14 expands drawing in air through the valve 21, the valve 18 closing during this operation, and thereby causing the air which has already passed through the perforations 105 13 to find its way through the shoe around and beneath the foot of the wearer, thereby ventilating the shoe.

From this description it will be seen that I have devised a very simple device by 110 which an article of footwear will be thoroughly ventilated by means which is sim-

ple, inexpensive, easily manufactured, and which cannot get out of order.

What I claim as my invention is:

1. In an article of footwear, the combination with the outsole provided with a chambered portion located between the instep and the point of the shoe terminating at its forward end in a duct having an enlarged extremity, a flexible bag located in the chamber, a valved duct connecting the rear of the bag with the atmosphere, a valved outlet at the opposite end of the bag adapted to discharge the air into the duct enlargement, and means within the bag for expanding the bag after each collapsing movement, and an insole extending over the chamber bag and duct enlargement and provided with perforations over said duct enlargement.
2. In an article of footwear, the combination with the outsole having a chamber located between the instep and the point of the sole, terminating at its forward end in a duct having an enlargement at its outer

end, a flexible bag located in the chamber provided at one end with a valved inlet and at its opposite end with a valved outlet located within the aforesaid duct, a series of resilient tubes located in the bag to hold the bag in its normally expanded position and an insole provided with perforations located over the duct enlargement. 25

3. In an article of footwear, the combination with the outsole chambered out between the instep and the point of the sole, of a duct extending forward from the chambered portion terminating in an enlargement, a flexible bag fitting the chamber having an inlet at one end and an outlet at the opposite end, flutter valves for controlling the inlet and outlet of air, a tube leading from the atmosphere to the aforesaid inlet, yieldable means for holding the bag normally expanded, and an insole provided with perforations over the aforesaid duct enlargement. 35 40 45

WELLINGTON LAURENCE MANSON GENDRON.
